US00D601129S

(12) **United States Design Patent**
Maruska et al.

(10) **Patent No.:** **US D601,129 S**
(45) **Date of Patent:** **** Sep. 29, 2009**

(54) **PORTION OF A REMOTE CONTROLLER**

(75) Inventors: **Joshua David Maruska**, Seattle, WA (US); **Philipp Steiner**, Seattle, WA (US); **John Dan Mabry**, Seattle, WA (US)

(73) Assignee: **Microsoft Corporation**, Redmond, WA (US)

(**) Term: **14 Years**

(21) Appl. No.: **29/246,023**

(22) Filed: **Jan. 4, 2006**

(51) **LOC (9) Cl.** **14-03**

(52) **U.S. Cl.** **D14/218**

(58) **Field of Classification Search** **D14/218, D14/455, 138 R, 138 AA, 138 AB, 138 AC, D14/138 AD, 138 G; D13/168, 199; D21/566; D10/104, 106; 345/169; 348/14.05, 114, 348/211.99, 734; 455/92, 5, 128, 151.31–151.4, 455/352, 355; 700/65; D24/186**

(57) **CLAIM**

The ornamental design for a portion of a remote controller, as shown and described.

DESCRIPTION

FIG 1 is a front perspective view of a portion of a remote controller showing our new design;

FIG. 2 is a front elevation view thereof;

FIG. 3 is a right side elevation view- thereof;

FIG. 4 is a left side elevation view thereof;

FIG. 5 is a top plan view thereof;

FIG. 6 is a bottom plan view thereof; and,

FIG. 7 is a rear elevation view thereof.

The broken line showing of the remainder of the remote controller is for illustrative purposes only and forms no part of the claimed design.

1 Claim, 5 Drawing Sheets
